CLAIM

The ornamental design for an combined coupon holder and advertising display for store shelving, as shown and described.

DESCRIPTION

FIG. 1 is a perspective view of a combined coupon holder and advertising display for store shelving showing my new design, with the broken line showing for illustrative purposes only and forming no part of the claimed design;

FIG. 2 is a right side view thereof;

The left side view is not shown, but is a mirror image of the right side view of FIG. 2. In all other respects it is identical to FIG. 2;

FIG. 3 is a top plan view thereof;

FIG. 4 is a front view thereof;

FIG. 5 is a rear view thereof;

FIG. 6 is a bottom plan view thereof; and,

FIG. 7 is a perspective view thereof; with the broken line showing for illustrative purposes only and forming no part of the claimed design.
